LEATHER CUTTING MACHINE

William C. Shields, Bombay, N. Y.

Application October 15, 1936, Serial No. 105,806

1 Claim. (Cl. 164—23)

This invention relates to leather cutting machines operable either pneumatically, hydraulically or electrically and has for the primary object the provision of a device of this character whereby the cutting of the work is by pressure so as to operate with a minimum amount of vibration and with efficiency and rapidity and is so constructed that the presser may be easily and quickly moved laterally of the work holder to permit work and cutting dies to be placed on and removed from the holder and the latter being so arranged that it may be easily adjusted to accommodate work of different thicknesses.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a front elevation illustrating a leather cutting machine constructed in accordance with my invention.

Figure 2 is a top plan view illustrating the device.

Figure 3 is a vertical sectional view illustrating the device.

Figure 4 is a horizontal sectional view taken on the line 4—4 of Figure 3.

Figure 5 is a fragmentary vertical sectional view illustrating the operation of the device by electrical means.

Figure 6 is a fragmentary front elevation showing said electrical operating means.

Referring in detail to the drawings, the numeral 1 indicates a base or bed having rising therefrom a supporting structure 2 of hollow formation terminating at its upper portion in a horizontally disposed arm 3 forming a support for a vertically arranged bearing 4 of the sleeve type. The supporting structure 2 also carries a lower sleeve type bearing 5 arranged in vertical alignment with the bearing 4. The bearings 4 and 5 slidably support a vertical shaft 6 to which is adjustably secured a horizontally arranged presser 7. The presser 7 besides being adjustable vertically on the shaft 6 is free to rotate on said shaft, a bearing 8 being provided to permit free rotation of the presser. The presser 7 is preferably of hollow formation having a die engaging face 10 and is strengthened by reinforcing ribs 11.

The supporting structure 2 has slidably mounted thereon a work support 12 including a re-

movable block 13 disposed horizontally for supporting the work to be acted upon by the presser. Tie bolts 14 are employed for detachably securing the block 13 to the support 12. The block 13 may be constructed of wood or any composition of material. The work support 12 is mounted also upon hand operated adjusting members 15 carried by the base 1. The hand operated adjusting members 15 permit the work support to be leveled and to be raised and lowered. The supporting structure includes a curved rest 16 acting as a stop for limiting the downward movement of the heel portion 17 of the presser. Suitable lubricating means 18 is provided for the shaft 6 and the journal of the presser.

The supporting structure 2 carries a bracket 19 to which is pivoted a lever 20, one end of which is pivotally and detachably connected to the lower end of the shaft 6. The other end of said lever is pivoted to a link 21. The link 21 is pivoted to a link 22 which is in turn pivoted to the supporting structure 2. The pivotal connection between the links 21 and 22 is indicated by the character 23 and connects to a head 24. The head 24 is disposed horizontally and is connected to a piston stem 25 of a piston 26 operating in a horizontally arranged cylinder 27. The cylinder is suitably attached to the supporting structure 2 and opposite ends thereof are connected to pipes 28 and 29. The pipes 28 and 29 are connected to a conventional type of two-way control valve 30 mounted on the presser 7. The pipes have flexible connection with the control valve so that the presser may swing horizontally in either direction or move vertically. A supply pipe 31 is connected to the control valve and to a pressure supply source (not shown). The pipe 31 has a flexible connection with the valve. The valve 30 may be operated in its different positions by a control lever 32 mounted on the presser. The valve 30 is adapted to admit pressure to either end of the cylinder to act on the piston for operating the latter in either direction for the purpose of raising and lowering the presser through the links 22 and 21 and lever 20 connected to the shaft 6.

In operation, leather or similar work is placed upon the block 13 and the die (not shown) placed upon the work. The control valve 30 is then actuated to admit pressure to the left hand end of the cylinder forcing the piston 26 to the right drawing the presser downwardly, bringing about severance of the work by the die. A reverse operation of the valve 30 causes a reverse move-

ment of the piston raising the presser so that the work may be removed along with the die.

The rear portion of the supporting structure has a hand opening closed by a removable cover

5 33. The pressure admitted to the cylinder may be either pneumatic or hydraulic.

After the work support has been adjusted vertically by the adjusting members 15 it may be secured in its adjusted position by stud bolts 35.

10 While I have described the presser as being operated either pneumatically or hydraulically, said presser may be successfully operated electrically by substituting a bell crank lever 37 for the link 22 and eliminating the head 24, cylinder 27 and all parts associated therewith. The bell crank lever 37 is pivoted to the base or stand, as shown in Figure 5, and has an electric solenoid 38 connected thereto. The electric solenoid is mounted on the base or stand in lieu of the cylinder 27 and its control may be in any conventional way. When the solenoid is energized it brings about pivotal movement of the bell crank lever and the latter in turn rocks the lever 20, lowering the presser. A spring is connected to the pivot 23 and acts to restore the presser to

its uppermost position when the solenoid is de-energized.

Having described the invention, I claim:

A leather cutting machine comprising a supporting structure including a hollow portion, vertically arranged bearings carried by said supporting structure, a shaft slidably supported by said bearings, a horizontally disposed work holder mounted on said supporting structure and having a vertical adjustment thereto and said supporting structure including an integrally formed extended portion arranged on the opposite side of the shaft from the work holder to provide a rest, a horizontally disposed presser journaled on the shaft and held against end- 15 wise movement thereon and including a heel portion to contact the rest for limiting the downward movement of the presser and to positively preclude further downward movement of the presser relative to said work holder when said 20 heel portion contacts said rest, linkage mounted in the hollow portion of the supporting structure and connected to the shaft, and a manually controlled power means connected to said linkage.
